US00D497260S1

(12) **United States Design Patent** (10) Patent No.: **US D497,260 S**
Hennel et al. (45) Date of Patent: **** Oct. 19, 2004**

(54) **APERTURED CONTINUOUS FILAMENT FABRIC**

(75) Inventors: **Gary Hennel**, Troutman, NC (US);
Nick Carter, Mooresville, NC (US)

(73) Assignee: **Polymer Group, Inc.**, North
Charleston, SC (US)

(**) Term: **14 Years**

(21) Appl. No.: **29/194,425**

(22) Filed: **Nov. 24, 2003**

(51) LOC (7) Cl. **05-05**

(52) U.S. Cl. **D5/47**

(57) **CLAIM**

The ornamental design for an apertured continuous filament fabric, substantially as shown and described.

DESCRIPTION

The sole FIGURE is an enlarged, fragmentary front elevational view of an apertured continuous filament fabric embodying the present design, with the opposite elevational view being identical.

1 Claim, 1 Drawing Sheet
